PAIR OF SUNGLASSES OR THE LIKE

Atherton R. Mitchell, Dillon Beach, Calif., assignor to Sea & Ski Corporation, Millbrae, Calif.

Filed Oct. 11, 1965, Ser. No. 87,424

Term of patent 14 years

(Cl. D57—1)

FIG. 1

FIG. 4

FIG. 2

FIG. 3

FIG. 1 is a top plan view of a pair of sunglasses, showing my new design.

FIG. 2 is a front elevational view thereof.

FIG. 3 is a side elevational view thereof.

FIG. 4 is a view similar to FIG. 1 with the glasses turned upside down.

I claim:

The ornamental design for a pair of sunglasses or the like, as shown.
